UNITED STATES PATENT OFFICE.

WINFRED M. BROOKS, OF WEST ORANGE, NEW JERSEY.

LEAD-HEADED NAIL.

Application filed November 22, 1924. Serial No. 751,439.

This invention relates generally to lead-headed nails used for roofing or similar purposes and has for its main object and feature reduction in the amount of lead used in their production without impairing their sealing qualities.

In the accompanying drawings the invention is disclosed in a concrete and preferred form in which:

10 Fig. 1 is a view in elevation of a nail embodying the invention.

Fig. 2 is a view similar to Fig. 1 with the body of lead in section.

15 Fig. 3 is a view similar to Fig. 2 but after the body of lead has been reduced by hammer blows.

20 Nails of this character are driven in by hammer blows, the body of lead surrounding the head of the nail being flattened in the process. It will be understood that the body of lead forms a sealing disk around the head of the nail. Owing to the difficulty of imbedding the head of the nail in a body of lead, a difficulty resulting from the chilling 25 effect which the head of the nail has upon the molten lead, it has been the custom to form the outer surface of the body of lead with a pronounced convex surface to thereby assure free flow of the molten metal 30 around and beneath the head of the nail. This form of the body of lead results in the use of an unnecessary amount of lead for sealing purposes and consequently increases the cost of production.

35 I find that the amount of lead used may be diminished without impairing the sealing qualities of the lead disk and without interfering with the free flow of metal when pouring the molten lead around the head of the nail.

40 1 indicates a nail having a head 2. Around this head is applied a body of lead 3 consisting of a main body 4 and a dome 5.

On its outer side the main body is formed with two taper surfaces 6 and 7, one above 45 the other, these surfaces meeting substantially in the plane of the head of the nail and lower surface 7 tapering more abruptly, with respect to the longitudinal center line of the nail, than upper surface 6. The result is that when pouring the molten lead into the mold, the metal will flow outwardly sufficiently far away from the head of the nail as not to be unduly chilled and will then take a more abrupt drop, with respect to the 50 longitudinal center line of the nail, as the metal passes beneath the head of the nail. When the body of lead is subjected to hammer blows substantially the formation indicated in Fig. 3 is obtained. As there 55 shown the outer circumference 8 of the sealing disk is of less thickness than the main portion 9 thereof but this does not interfere with the sealing qualities of the disk since the circumference of said disk is substantially equal to that of the disk produced by the old method. The amount of metal saved 60 is indicated in dotted lines at 10 in Fig. 3.

I claim:

A nail the head of which is imbedded in 70 a body of lead, said body of lead having on its outside two taper surfaces, one above the other and meeting substantially in the plane of the head of the nail, the lower surface tapering more abruptly, with respect to the 75 longitudinal center line of the nail, than the upper one, to thereby allow free flow of the molten metal and to form, when subjected to blows, a sealing disk the outer circumference of which is of less thickness than the 80 main portion thereof.

Signed at 98 Park Place, in the county of New York and State of New York, this 20th day of November, 1924.

WINFRED M. BROOKS.
